ROLLER STRAIGHTENING MACHINE

Alfred Wirth, Erkelenz, Rheinland, Germany

Application July 6, 1931, Serial No. 549,033, and
in Germany July 11, 1930

6 Claims. (Cl. 153—54)

This invention relates to a roller straightening machine of the kind in which a housing, more particularly the outer housing, is movably arranged for the purpose of exchanging the straightening rollers and the straightening roller shafts. In these known roller straightening machines, one disadvantage in particular is present, namely that the total length of the machine in the operative condition and its total length in the open condition are different from one another. A great deal of space of the available cooling bed surface is thereby regularly taken up.

In order to remove this disadvantage, according to the present invention a fundamentally different course is adopted. The main idea of the invention is to be found in the fact that the inner housing provided between the gear box and the outer housing is slidably arranged. In this way the total length of the roller straightening machine is constant for all operative circumstances.

The above-mentioned structural arrangement also yields further important advantages. Thus the possibility is given of supporting the straightening roller shafts in such a way that when the inner housing is shifted they remain connected with it. In order to preclude tilting moments, according to the invention, the straightening roller shafts and the driving shafts supported in the driving box are guided one in the other.

Further details of the invention will appear from the following description of a constructional example.

The invention is illustrated in the accompanying drawings, in which

Figure 1 shows a roller straightening machine according to the invention in section in the working condition,

Figure 2 shows the same machine, likewise in section, but in the separated condition,

Figure 3 is a view of the outer housing of the machine, and

Figure 3a a side view of the outer housing.

Upon the base *a* of the roller straightening machine are lodged the driving box *b*, the outer housing *c* and the inner housing *d*, these being mounted in such a way that the outer housing *c* and the driving box *b* are fixed to the base, while the inner housing *d* is displaceable upon the base *a* between the outer housing and the driving box.

Figure 1 shows the straightening roller shafts *e* and *f*, with the straightening rollers *g* and *h*, which are supported in the housings *c* and *d*. As supporting means, double thrust chambers *i* are provided in the stationary outer housing *c*.

In these double thrust bearing chambers are also provided screws *j*, which, by being rotated, can be screwed into a threaded bore *y* in the end of each straightening roller shaft, so that the straightening roller shafts are thereby secured 60 in the simplest manner when the machine is in the working condition and end and radial thrusts of the roller shafts are transmitted to the bearing chambers. This provision is also made for the purpose of permitting convenient removal of the roller shafts as, for instance, to facilitate changing thereof. The thrust chamber is rotatable in a bearing sleeve *k* which latter is adapted to take up radial thrust and is provided with a collar *u* cooperating with 70 two sets of bearing balls *v* and *v'* adapted to take up axial thrust. The thrust bearing is surrounded by a cylindrical casing *n* which is secured in the housing *c* and provided with an adjustable nut *n'* for adjusting the races of the 75 bearing balls *v* and *v'* to compensate for wear. A further advantage in the provision of this thrust chamber and the mounting thereof in the housing *c* is the protection of the bearing surfaces which, when the rollers are being changed, 80 are not exposed to damage, due to the fact that during this operation the thrust chamber remains in position in the housing *c* and the roller shafts are withdrawn therefrom.

In the displaceable inner housing *d* plain journal bearings *k* are also provided for the reception of the ends of the straightening roller shafts. With the ends of the straightening roller shafts that are lodged in the inner housing, the driving shafts *l* of the driving box *b* are connected. For the sake of greater clearness in the drawings only one driving shaft is shown. The driving shaft is slidably keyed in its driving member *l'* in the driving box so as to be slidable in an axial direction, whereby adjustment of the 95 inner housing *d* and the driving shaft *l* may be effected. For the shifting of the inner housing, it is sufficient to provide a single screw spindle *m*, which is secured to the housing *d* and moved axially by a suitable controlling device on the outside of the driving box, for instance, a worm wheel *m'* threaded thereon. The end *o* of the double thrust chambers forms an abutment shoulder, against which the straightening rollers *g* are tightly drawn when the screws *j* are tightened, so 105 that these rollers are secured in their proper position without special auxiliary means such as ring nuts or the like being required.

For operating the straightening rollers there serves a motor *p*, which is located on the outside 110

of the fixed outer housing, and which acts through clutches *q*, preferably operated by hand levers *r*, upon the operating gear and therefore upon the various straightening roller shafts. The actuating of the straightening rollers may of course be effected by providing a separate motor for each straightening roller shaft. The essential point is that owing to the arrangement adopted according to this invention of making the outer housing stationary, the possibility is provided of designing the outer side of the outer housing as a central operating position for the machine.

In both housings oil chambers *s* are provided, by which all the running surfaces of the straightening roller shafts and of the double thrust chambers are automatically lubricated. When the straightening roller shafts, with the straightening rollers, are to be changed, it is only necessary to unscrew the screws *j* shown in Figure 1 so far that the engagement between the straightening roller shafts and the screws is released. The inner housing *d* can then without further difficulty be moved into the position shown in Figure 2 by means of the worm wheel *m'* and the screw spindle *m*. The circumstance that the straightening roller shaft, through the driving shafts *l*, still remains in guiding connection with the driving box, is particularly advantageous, since in this way the tendency of the housing *d* to tilt over under the weight of the straightening roller shafts, with the straightening rollers, is obviated. In the removed condition according to Figure 2, sufficient space is provided for running through the machine any materials that are not to be straightened between the ends of the straightening shafts and the inner wall of the stationary outer housing *c*. The re-establishment of the working condition is likewise effected in the simplest manner by moving the displaceable inner housing *d* back to the stationary outer housing and screwing into the ends of the straightening roller shafts the assembling and releasing screws *j* located on the outer housing. Then finally the end faces of the straightening rollers are drawn against the shoulder of the thrust chamber, so that the correct adjustment of the straightening rollers is ensured without special precautions having to be taken.

What I claim is:—

1. A roller straightening machine including gearing for driving the straightening rollers, a stationary driving box carrying the whole of the driving gearing, a stationary outer housing, and an inner housing slidably mounted between the driving box and the outer housing. 80

2. A machine as claimed in claim 1, including straightening rollers, shafts supporting said rollers and supported partly in the outer stationary housing and partly in the slidable housing and adapted, when the latter is displaced, to move therewith and to disengage the outer stationary housing. 85

3. A machine as claimed in claim 1, including rollers, shafts supporting said rollers and rotatably supported partly in the slidable housing and partly in the stationary housing, drive shafts slidably guided in the driving box and rigidly connected with the roller supporting shafts to prevent tilting of the slidable housing when the latter is moved away from the stationary outer housing. 90 95

4. A machine as claimed in claim 1, including a double thrust bearing chamber rotatably mounted in the outer stationary housing and having an abutment shoulder thereon, a roller supporting shaft removably received in the bearing chamber, and a retaining screw rotatable in the bearing chamber and threaded in the terminal of the roller shaft to retain the latter in the bearing chamber. 100 105

5. A machine as claimed in claim 1, including an actuating device for the slidable housing including a screw connected with said slidable housing and passing through the box. 110

6. A roller straightening machine including gearing for driving the straightening rollers, a stationary driving box carrying the whole of the driving gearing, an inner housing slidably mounted between the driving box and the outer housing, a shaft journaled in the outer and inner housings, a driving connection between the driving gear and said shaft, and means connecting said shaft and driving member with the inner housing whereby, when the latter is displaced, said shaft and member move therewith. 115 120 125
